UNITED STATES PATENT OFFICE.

HARRY P. DAVIS, OF PITTSBURGH, AND CHRISTIAN AALBORG, OF WILKINSBURG, PENNSYLVANIA, ASSIGNORS TO WESTINGHOUSE ELECTRIC & MANUFACTURING COMPANY, A CORPORATION OF PENNSYLVANIA.

CIRCUIT-INTERRUPTER.

1,140,961.

Specification of Letters Patent. Patented May 25, 1915.

Original application filed June 25, 1906, Serial No. 323,353. Divided and this application filed May 27, 1912. Serial No. 699,973.

To all whom it may concern:

Be it known that we, HARRY P. DAVIS and CHRISTIAN AALBORG, citizens of the United States, and residents, respectively, of Pittsburgh and of Wilkinsburg, in the county of Allegheny and State of Pennsylvania, have invented a new and useful Improvement in Circuit-Interrupters, of which the following is a specification, this application being 10 a division of application Serial No. 323,353, filed June 25, 1906.

Our invention relates to circuit-breakers and has special reference to such devices as are adapted to automatically interrupt electric circuits upon the occurrence of predetermined conditions therein.

The object of our invention is to provide a circuit-breaker of the class above indicated, which shall be simple and durable in 20 construction, electrically operated, automatically actuated to interrupt the circuit under predetermined conditions and manually actuated under certain other conditions, and specially adapted for outdoor service.

25 In the application of a relatively high-voltage trolley line construction to general railway service, it is desirable to divide the trolley line into sections, which may be readily disconnected from the source of supply so that repairs may be effected without danger. Circuit interrupters which are employed for this purpose must be amply protected from weather conditions and arranged so that the operating parts may be inspected 30 and repaired without danger of injury to the attendant. In order to accomplish the aforesaid objective results, the circuit-breaker of our present invention is entirely inclosed in a water-tight casing, is electrically operated and is provided with an automatic tripping mechanism, which may be 35 actuated when the current traversing the circuits completed through the switch exceeds a predetermined amount or when the cover 40 of the inclosing casing is removed or moved to open position. The overload tripping device is so arranged that the electric operating mechanism will not close the switch when the tripping coil is energized.

45 50 As is usual in high-voltage circuit-breakers, the operating contact members which are first separated when the circuit is interrupted are oil-immersed but the stationary

members, instead of being directly connected to the line conductors, as is the usual arrangement, are connected to a second set of stationary members by means of bridging contact switch members that are relatively stationary and are supported by and insulated from the cover. The second set of stationary terminal members are connected to the line conductors and are so embedded in insulation that, when the cover is open, the exposed contact members are thoroughly protected and are almost inaccessible to an 55 60 65 inspector or attendant who may be employed in repairing the operating mechanism.

Figure 1 of the accompanying drawings is a view, mainly in elevation but partially in section, of a circuit interrupter constructed in accordance with our invention and Fig. 2 is a plan view of the interrupter with the cover partially broken away.

Referring to the drawings, the circuit interrupter illustrated comprises stationary 75 contact members 1, 2, 3 and 4, movable bridging contact members 5, 6, and 7, an inclosing casing 8, having a hinged cover 9, a detachable fluid-containing tank 10, and on operating mechanism 11. The stationary 80 contact members 2 and 4 comprise vertical rods 12 of conducting material, which are attached to, and insulated from the bottom of the casing 8 by means of molded insulating supports 13. The lower ends of the rods 85 12 project from holes in the bottom of the casing and are provided with terminal members 14, to which line conductors may be attached. These members are protected by bell-shaped insulators 15, which are fitted 90 into the lower ends of the insulators 13 and form a tapered plug and sleeve connection therewith. The upper ends of stationary members 2 and 4 are provided with forked projections 16 and 17, which are adapted to 95 be respectively engaged by the bridging contact members 5 and 6. The upper portions of the stationary contact members 1 and 3 are similar to those of the members 2 and 4, being provided with forked terminal members 18 and 19 which are adapted to be engaged by the opposite ends of the bridging contact members 5 and 6. The lower ends of the members 1 and 3 extend through suitable holes in the casing 8, from which they 100 105 are separated by insulators 20 and are pro-

vided with resilient cup-shaped terminal members 21 of a well known construction, such as are shown and described in Patent No. 758,621, granted to Westinghouse Electric & Manufacturing Company, as assignee of Harry P. Davis. The movable contact member 7 that is adapted to engage the stationary resilient members 21, is connected to an operating lever 22 by a link 26 and 5 is located, together with stationary members 21, in the fluid-containing tank 10. The upper end of the link 26 is pivotally connected to a clamp 27 that is attached to and insulated from the operating lever 22. In this 10 way, the operating mechanism 11 is exempt from any possibility of becoming electrically connected to the supply circuit. The bridging contact members 5 and 6 are relatively stationary, both being mounted upon 15 insulators 28 that are attached to the inside of the cover 9. The cover 9 is provided with a flange 9^a which overhangs the upper edge of the casing 8, so that water is prevented from running into the casing, and 20 it is pivotally mounted upon hinge pins 29, which are supported by forked projections 30 on the outside of the casing. In order to raise and lower the cover, which may be 25 relatively heavy, a handle lever 31 is pivotally mounted upon a stationary shaft 32 that projects from the side of the casing and is connected to the cover 9 by means of a forked projection 33 and a link 34. The arrangement of parts is such that the cover 30 may be swung open through a predetermined angle and held in such position until the handle lever is swung back through a small angle to release it.

40 The operating mechanism 11, is described in detail and claimed in my copending application, Serial No. 323,353, of which this application is a division, and forms no part of my present invention. It comprises, in 45 general, the operating lever 22 which is fulcrumed at an intermediate point in its length, an operating magnet 46, a bell crank lever 37 and a tripping magnet 38. The lever 37 is so arranged that movement there- 50 of through a predetermined angle in the one or the other direction serves to actuate the operating lever 22 and thereby move the bridging member 7 into and out of engagement with the contact members 21. The 55 magnet 46 operates directly on a lever 49 which imparts its motion to an arm 43 of the lever 37. The bell crank lever 37 is connected to the lever 22 by a link 41 and is connected to the lever 49 by a latch 44. The 60 arrangement of parts is such that the lever 49 and the lever 37 act together except when the tripping magnet 38 is energized. Under these conditions, the latch 44 is released and it is impossible to close the circuit breaker by energizing the operating mag- 65 net 46.

Although I have shown a specific structure, I desire that variations in size, form and arrangement of parts which do not materially change the mode of operation or result shall be included within the scope of my 70 invention, and that only such limitations shall be imposed as are indicated in the appended claims.

I claim as my invention:

1. A switching device for an electric circuit comprising two pairs of stationary contact terminals, a coöperating movable contact member for one pair of terminals, and an inclosing casing having a movable cover provided with members for electrically connecting corresponding stationary terminals of the two pairs together and for coöperating with the movable contact member to close the circuit when the cover is closed and acting to open the circuit when the 85 cover is opened.

2. The combination with a pair of stationary conducting rods provided with supporting bushings of insulating material and having resilient, cup-shaped oil-immersed 90 contact terminals at their lower ends and contact terminals at their upper ends, a movable bridging contact member to coöperate with said lower terminals, a second pair of similarly mounted stationary conducting 95 rods having circuit terminals at their lower ends, and contact terminals at their upper ends, of an inclosing and supporting casing for the stationary parts, a cover therefor, switch blades mounted on and insulated 100 from the cover and adapted to connect corresponding upper contact members of the two pairs.

3. The combination with a pair of stationary conducting rods provided with supporting bushings of insulating material and having contact terminals at their lower ends and contact terminals at their upper ends, a movable bridging contact member that co- 105 operates with said lower terminals, a second 110 pair of similarly mounted stationary conducting rods having contact terminals at their upper ends, of an inclosing and supporting casing for the stationary parts, a cover therefor, switch blades mounted on, 115 and insulated from, the cover and adapted to engage corresponding upper contact members of the two pairs.

4. The combination with four stationary conducting rods provided with supporting 120 bushings of insulating material two of which have contact terminals at their lower ends, a fluid-containing tank surrounding said terminals and a movable bridging contact member which coöperates therewith, stationary 125 connectors attached to the lower ends of the other two rods, and contact terminals on the upper ends of all of the rods, of an inclosing casing, a cover therefor, switch blades mounted upon and insulated from the cover and 130

adapted to so engage the upper contact terminals, when the cover is closed, that the circuit is completed from one stationary connector through one switch blade, the mov-

5 able bridging contact member and the other switch blade, to the opposite connector.

5. In a switching device for an electric circuit, the combination with a supporting frame, and a casing having a movable cover, 10 of a pair of stationary terminals to which line conductors may be attached, a second pair of stationary terminals, a coöperating movable bridging contact member for said second pair of terminals, and means mounted on the cover and serving to open and close the circuit when the cover is respectively opened and closed.

6. In a switching device for an electric circuit, the combination with a supporting frame, and a casing having a movable cover, 20 of a pair of stationary terminals to which line conductors of the circuit may be attached, a second pair of stationary terminals, a coöperating movable bridging contact member for said second pair of terminals, and switching means attached to the cover

for interconnecting the two pairs of stationary contact terminals when the cover is closed and for opening the circuit when the cover is opened.

30

7. The combination with a pair of stationary conducting rods having contact members on both ends thereof, a movable bridging contact member to coöperate therewith, a second pair of stationary conducting rods having contact members at their upper ends and circuit terminals at their lower ends, of an inclosing casing for the stationary parts, a cover therefor, and switch blades mounted on and insulated 35 from the cover for connecting the upper contact members of the two pairs of stationary conducting rods.

In testimony whereof, we have hereunto subscribed our names this 11th day of May, 1912.
